Primary Examiner — Wan Laymon*(74) Attorney, Agent, or Firm* — NSIP Law(57) **CLAIM**

We claim the ornamental design for a beam projector, as shown and described.

DESCRIPTION

FIG. 1 is a front perspective view of a beam projector showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view showing a state of use in which the main body is shown in a rotated position;

FIG. 9 is a perspective view showing a state of use in which the main body is shown in a opposite rotated position; and,

FIG. 10 is a perspective view showing a state of use in which the lens cover is shown in a combined state with the main body of the beam projector.

(Continued)

The broken lines in the figures depict environmental structure and portions of the beam projector and form no part of the claimed design.
